UNITED STATES PATENT OFFICE.

LEE ANDERSON, OF PARIS, TEXAS, ASSIGNOR OF ONE-HALF TO HARRISON S. BETTES, OF SAME PLACE.

NON-REFILLABLE BOTTLE.

SPECIFICATION forming part of Letters Patent No. 665,046, dated January 1, 1901.

Application filed June 4, 1900. Serial No. 18,969. (No model.)

To all whom it may concern:

Be it known that I, LEE ANDERSON, a citizen of the United States, residing at Paris, in the county of Lamar, State of Texas, have invented certain new and useful Improvements in Non-Refillable Bottles, of which the following is a specification, reference being had therein to the accompanying drawings.

This invention relates to non-refillable bottles, and more particularly to means for admitting air to such bottles, in connection with a valve-stopper for preventing the introduction of liquid into the bottle after the stopper has been placed in position.

The invention has for its object to locate an air-vent passage and chamber in communication with the neck of the bottle and adjacent to the inlet into the bottle, in connection with a valve which when in position will close this vent-passage and also the inlet to the bottle.

The invention also has for an object to improve the general construction of the stopper by which when the valve is placed in position it cannot be tampered with by the introduction of any instrument through the stopper.

Other objects and advantages of the invention will hereinafter appear in the following description, and the novel features thereof will be particularly pointed out in the appended claims.

In the drawings, Figure 1 is a vertical section with the bottle in an upright position. Fig. 2 is a similar view with the bottle upon its side. Fig. 3 is a similar view with the bottle inverted for the purpose of pouring the liquid therefrom. Fig. 4 is a detail perspective of the stopper and locking-ring, and Fig. 5 is a similar view of the valve and pendent weight.

Like letters of reference indicate like parts throughout the several figures of the drawings.

The letter A designates a bottle, the body of which may be of any desired configuration and which is provided at its upper portion, adjacent to the neck, with inclined walls A', substantially conical in shape, as shown in the drawings. Above this conical portion the neck A² extends and is provided at its lower part with a valve-seat A³. At one side of the bottle the neck is provided with an enlarge-

ment A⁴, provided with a vent-passage A⁵, inclining downwardly from a communication with the neck of the bottle. At the outer end 55 of this passage an air-chamber A⁶ is provided, which at its upper and lower portions is supplied with minute perforations or apertures A⁷ for admitting air into the chamber. By locating these at opposite ends of the chamber it will be seen that the hand of the user is not liable to close both sets of openings at any time, and thus check the flow of liquid from the bottle. It will also be seen that by 60 inclining the vent-passage to the neck of the bottle and extending it for a distance therefrom the air-inlet perforations will be raised, when the bottle is in position for pouring its contents, so that, on the other hand, it will not be checked by any liquid which may flow 65 from the bottle nor will such liquid escape through the perforations. In connection with 70 this vent-passage and the neck of the bottle I have provided an improved form of valve B, which may be conical or of other desired shape 75 and is adapted at its lower end B' to seat upon the valve-seat A³, while the periphery or side wall of this valve closes the air-vent A⁵ when in a closed position. The upper portion of the valve is also provided with a cup B², 80 adapted to receive any liquid which may be introduced into the bottle-neck, and thus force the valve to its seat, preventing the introduction of the liquid beyond the neck of the bottle. The under face of this valve is 85 also provided with a seat B³, into which one end C' of a pendent weight C is adapted to extend. This weight C controls by gravity the action of the valve and also by a similar force assists in holding the valve closed and 90 finally in opening the valve when desired. The weight is suspended from the valve by any flexible means—for instance, a cord C²—so that it may assume any desired position within the bottle relative to the valve B—for 95 instance, as shown in Fig. 2, where the weight C rests upon the wall A' of the bottle and prevents the pressure of liquid from opening the valve when the bottle is in the position there shown. If the bottle be inverted into the position for permitting the liquid to flow therefrom, the end C' of the weight acts as a plunger or pusher for opening the valve and 100 resisting any tendency to stick which may ex-

ist. In fact, if the valve be difficult to open it can be readily jarred from its seat by a slight reciprocation of the bottle, which throws the weight C against the valve, thus easily 5 jarring it into the proper position for withdrawing the liquid from the bottle.

While it is obvious that any desired form of stopper or cork may be used in connection with the vent and valve herein described, 10 yet I present herewith a very desirable form, which embodies a stopper D, having a central aperture D' for the outflow of liquid, which communicates at its lower end with cross-channels D² and inlets D³, thus presenting 15 a circuitous path for the liquid, and a solid wall D⁴, directly beneath the main outlet D', which prevents any tampering with the valve D, located beneath the stopper or guard. This stopper is also locked in position by 20 means of a spring or elastic ring E, of metal or other suitable material, which is seated partially in a recess D⁵ in the stopper and partially within a similar recess E' in the neck of the bottle. It will be seen that when this 25 ring is sprung into position in the recesses D⁵ and E' the stopper will be effectually locked within the neck of the bottle.

From the foregoing description the general 30 operation of the invention will be apparent, and it need only be stated in addition that when the bottle is originally filled with liquid the valve B is first dropped in position upon its seat, after which the stopper D is inserted and locked in position. These two 35 parts, in connection with the vent formed in the material of the bottle-neck, produce an effective stopper which prevents the introduction of liquid into the bottle and only permits the flow of liquid therefrom when the 40 bottle is held in proper position for that purpose. Furthermore, the vent communicating with the neck of the bottle tends to establish an uninterrupted flow of liquid from the neck of the bottle, as it supplies the necessary 45 air for that purpose at a point below or beyond the fixed stopper or guard, while the valve when in its closed position covers the inlet from the air-vent, thus preventing the deterioration of the contents of the bottle by reason of any air coming in contact 50 therewith. The invention also embraces important advantages in its simplicity of construction by reason of which it can be manufactured in a most economical manner and in 55 its operation produces the most efficient action sought for in this class of devices.

It will be obvious that changes may be made in the details of construction and configuration of the several features of structure without departing from the spirit of the invention 60 as defined by the appended claims.

Having described my invention, what I claim is—

1. A bottle having at the base of the neck 65 thereof a vent-passage extending laterally through said neck and communicating with the atmosphere at its outer end and having

its inner end immediately adjacent to the interior of the bottle whereby resistance to inflowing air by outflowing liquid, in the neck 70 proper, is avoided, substantially as specified.

2. In a bottle, the combination with the neck thereof, of a vent-passage extending at an angle to said neck and communicating with an elongated air-chamber provided with perforations at its opposite ends; substantially as specified.

3. In a bottle, the combination with the neck thereof, of a vent-passage extending at an angle to said neck and communicating with an 80 elongated air-chamber provided with perforations at its opposite ends, and a valve adapted to close the inlet of said vent into said neck; substantially as specified.

4. In a non-refillable bottle, the combination with a neck provided with an air-vent communicating therewith at its lower portion adjacent to a valve-seat, of a conical valve adapted to seat at the lower end of said neck and to close the inlet from said vent by its side 90 wall; substantially as specified.

5. In a non-refillable bottle, the combination with a neck provided with an air-vent communicating therewith at its lower portion adjacent to a valve-seat, of a movable valve 95 adapted to seat at the lower end of said neck and to close the inlet from said vent by its side wall, and a pendent weight flexibly supported from said valve; substantially as specified.

6. In a non-refillable bottle, the combination with a neck provided with an air-vent communicating therewith, of a valve adapted to seat at the lower end of said neck and to close the inlet from said vent, a pendent 105 weight flexibly supported from said valve, a stopper or guard above said valve provided with a longitudinal outlet and lateral passages communicating therewith, and means for locking said stopper in position; substantially as 110 specified.

7. In a non-refillable bottle, a neck portion having at its lower portion inclined walls extending to the body of said bottle, a vent-passage in said neck communicating with a perforated air-chamber, a sliding valve located in said neck and provided with a cup upon its upper face and a seat upon its lower face, and a pendent weight flexibly supported from said valve and extending into said seat; substantially 115 as specified.

8. In a bottle, a neck portion provided with a seat at its lower end, a vent-passage communicating with said neck adjacent to said seat, and a valve adapted to rest at its lower 125 end upon said seat and close said vent by its side wall; substantially as specified.

In testimony whereof I affix my signature in presence of two witnesses.

LEE ANDERSON.
